UNITED STATES PATENT OFFICE.

DAVID W. HAWKSWORTH, OF DETROIT, MICHIGAN, ASSIGNOR TO HUTCHINS CAR ROOFING COMPANY, OF DETROIT, MICHIGAN, A CORPORATION OF MICHIGAN.

CAR-ROOF.

1,130,280.

Specification of Letters Patent.

Patented Mar. 2, 1915.

Application filed December 2, 1910. Serial No. 595,255.

To all whom it may concern:

Be it known that I, DAVID W. HAWKSWORTH, a citizen of the United States of America, residing at Detroit, in the county 5 of Wayne and State of Michigan, have invented certain new and useful Improvements in Car-Roofs, of which the following is a specification, reference being had therein to the accompanying drawings.

10 The invention relates to car roofs of that type comprising purlins, metallic carlines, and roofing sheets supported thereon and spanning the spaces therebetween. It is usual with such constructions to arch the 15 carlines to conform to the pitch of the roof, the bend being at the ridge, and it is also usual to arrange the purlins both at the ridge and intermediate the ridge and the eaves beneath the carlines. An objection to 20 this construction is that the sides of the car are only tied together by the bent carlines and consequently there is nothing to prevent the spreading of the sides and the straightening of the carline under sufficient internal 25 pressure against the sides. This result frequently occurs where the car is loaded with grain or other material exerting a pressure against the sides, and the result is, first, the outward deflection of the sides, and second, 30 the lowering of the ridge so as to destroy the pitch of the roof.

It is the primary object of the present invention to limit the amount of deflection possible by the straightening of the carline 35 under strain and also to prevent the complete destruction of the pitch of the roof by the lowering of the ridge. This is accomplished by a novel construction of carline, and further by the construction, arrangement 40 and combination therewith of the purlins, roofing sheets, and other elements as hereinafter set forth.

In the drawings,—Figure 1 is a cross section through a car roof constructed in accordance with my invention; Fig. 2 is a longitudinal section on line $x-x$, Fig. 1; Fig. 3 is a longitudinal section in the plane of the center of the ridge; Fig. 4 is a plan view of a portion of the roof sheets adjacent 50 to the ridge. Fig. 5 is a view similar to Fig. 3 showing a modified construction.

A are the side plates of the car body structure and B is the central or ridge purlin arranged above the level of the plates to 55 obtain the desired pitch of roof. C are

metallic carlines comprising beams of suitable structural shape which as shown, is an inverted channel having laterally projecting flanges C' at the lower ends of its sides. These carlines instead of conforming to the 60 shape of the roof and extending above the ridge purlins as is usual with this type of structure, are formed to pass beneath the ridge purlins thereby shortening the length of beam between the side plates. Thus if 65 sufficient pressure is exerted against the sides of the car to straighten the carlines the maximum deflection possible is so slight as to be of no importance. Furthermore, the ridge instead of dropping to the level of the 70 plate, as is possible with the old type of construction, will be maintained above the level of the plates by a space equal to the depth of the ridge purlin and the carline combined, which is sufficient to still maintain 75 a drainage pitch to the roof.

In more specific construction, the carline preferably comprises a central straight portion C² which passes beneath the ridge purlin B, end portions C³ conforming to the 80 angle of the roof and separated from the central portion by the bend C⁴. These bends are preferably located substantially midway between the ridge purlin and the plates and an intermediate purlin D is arranged 85 to extend beneath the carlines adjacent to this bend. Thus, the carlines pass beneath the ridge purlin and the plane of the central portions of the roof sheets. At its ends the carline is secured to the side plates by 90 any suitable means that shown being a bracket E. The carlines are also secured to the intermediate purlin D and to the ridge purlin B by bolts F, and the structure is such that a pair of separated bolts may be 95 employed with each of said purlins which will hold them and prevent any swiveling at the point of attachment. This overcomes an objection to constructions heretofore used where by reason of the structure it is only 100 possible to pass a single bolt through the ridge purlin. With the present construction however, the fact that the carline passes beneath the ridge purlin, permits of bolting the web portion of the carline to the 105 purlin on opposite sides of the center thereof as shown in Fig. 1.

The roof sheets G as is usual with this type of roof construction are arranged to extend between carlines and from the ridge 110

to the eaves, being provided with upstanding weather proofing flanges G' at the opposite side edges thereof, and an upstanding flange G^2 at the ridge. These flanges are formed by pressing from a flat blank without slotting at the corners which necessitates the deflection of the extra metal at said corners. With constructions heretofore used, where the carline extends above the plane of the sheets throughout its entire length, and where the sheets span the space between carlines, it has been impossible to deflect this extra metal laterally by reason of the interference of the carlines and consequently it has been deflected toward the ridge necessitating a considerable clearance space between the ridge flanges of the plates on opposite sides of the car. With my improved construction the fact that the carline passes beneath the ridge purlin provides abundant clearance between adjacent sheets at the ridge so that the extra metal G^3 may be deflected laterally as shown in Fig. 4. This permits of reducing the clearance between the flanges G^3 of the plates on opposite sides of the ridge.

With the structure of roof frame thus far described the roof sheets are supported by resting upon the plate and ridge purlin at their opposite ends and upon the intermediate purlin F in their central portions, the spaces between said purlins and carlines being spanned by the sheet without any support. In case the sides of the car are spread and the carlines straightened there will be an equal lowering both of the ridge purlin and intermediate purlin F , due to the fact that the carline between the said intermediate purlin is straight. In thus lowering, the roof sheets will change their inclination but inasmuch as the central portion of the sheet will only be lowered one half the distance of travel of the end at the ridge, while the intermediate purlin is depressed a space equal to the lowering of the ridge, it is obvious that the roof sheet will separate from its support on the intermediate purlin. I therefore, make special provision for reinforcing the sheet which consists in longitudinal beads or corrugations H extending from the point of support on the plate to that on the ridge, these strengthening beads or ribs in connection with the reinforcement of the upstanding side flanges with their integral connection to the ridge flange, will greatly strengthen the plate so that the support of the intermediate purlin may be dispensed with. If however, the plate is not sufficiently rigid to remain out of contact with the intermediate purlin there will still be sufficient pitch to the roof to take care of drainage.

The flanges G' of the roof sheets are covered by the usual weather proofing caps I

and a ridge cap J which latter forms also a support for the saddle K to which the running boards L are secured. A central bolt M passing through the saddle, ridge cap, ridge purlin, and web of the carline will secure these parts in fixed relation.

Another advantage in the arrangement of the carline beneath the ridge purlin is that this permits of increasing the depth of the section in the central portion of the beam to strengthen the truss. This may be accomplished in several ways. As shown in Fig. 3, the laterally extending flanges C' are bent downward into an inclined position as indicated at C^4 . In Fig. 5 a modification is shown in which laterally extending flanges C' are continued throughout the length of the blank, but the sides C^5 are deeper at the center than at the ends. With both of these constructions as well as with others that may be devised, increased depth at the center of the beam produces the desired trussing effect.

What I claim as my invention is:

1. In a car roof, the combination with purlins, of a carline arranged beneath the ridge purlin and above the intermediate purlins.

2. In a car roof, the combination with a plurality of purlins, of a roof plate supported directly by said purlins, and a carline having different portions of the length extending upon opposite sides of different purlins.

3. In a car roof, the combination with a pitched roofing sheet, of a carline having different portions of the length thereof arranged with the neutral axis upon opposite sides of the plane of said roofing sheet.

4. In a car roof, the combination with metallic roofing sheets extending from eaves to ridge, of a carline extending from eave to eave having its outer portions projecting above the plane of the body of roofing sheets, and a central portion beneath the plane thereof.

5. In a car roof, the combination with a ridge purlin, and side plates, of pitched roofing sheets extending between said side plates and ridge, and a carline between adjacent sheets having its central portion beneath the ridge purlin and the plane of the body of roofing sheet, and its outer portions projecting above the plane of said sheet.

6. In a car roof, the combination with side plates and the ridge purlin, of a pitched roofing sheet extending from ridge to side plate, a carline extending between side plates having end portions conforming to the pitch of the roof and projecting above the plane of the body of roofing sheet, and a straight central portion extending beneath the ridge purlin.

7. In a car roof, the combination with

- side plates and the ridge purlin, of pitched roofing sheets extending therebeneath, and a carline extending between said side plates having its outer portions projecting above the plane of the body of said sheets and conforming to the pitch thereof, and a central portion extending beneath the ridge purlin, said central portion being of greater depth than the end portions.
8. In a car roof, the combination with side plates and the ridge purlin, of roofing sheets extending from ridge to side plates, and a carline having end portions projecting above the plane of the body of said sheets, and a central portion below the plane of said sheets and of a section progressively increasing in depth toward the center of the roof.
9. In a car roof, a metallic carline formed of an inverted channel bar, the end portions of said carline conforming to the pitch of the roof and having laterally extending flanges, and a central portion of said carline extending in a straight line upon opposite sides of the ridge and having laterally extending flanges depressed to form a greater depth section.
10. In a car roof, the combination with a ridge purlin, and side plates, roofing plates extending from said ridge to said plates, purlins intermediate said ridge and side plates, a carline having its outer portion extending above the plane of the roofing sheets and intermediate purlin, and its central portion beneath the plane of the roofing sheets and ridge purlin.
11. In a car roof, the combination with side plates, ridge purlin, and intermediate purlin, of a carline normally supporting said purlins in the plane of the roof sheet but adapted to depress the intermediate purlin below the plane of said sheet upon the spreading of the side plates, and a roof plate supported on said ridge purlin and side plates and normally on said purlins having upstanding edge flanges, and intermediate longitudinally extending ribs or corrugations for the purpose described.
12. In a car roof, a roof sheet having upstanding side and ridge flanges unbroken at the corner, the extra metal at the corner being deflected outward laterally of the side flanges, and a carline passing adjacent to the side flange of said sheet in a portion of the length thereof and deflected below the plane of said sheet at the point of lateral deflection of said corner.
13. In a car roof, the combination with a ridge purlin and an intermediate purlin, of a carline arranged beneath the ridge purlin and above the plane of said intermediate purlin.
14. The combination with a car roof pitched from ridge to eaves, of a carline having a portion conforming to the pitch of the roof and supporting the same, the total length of said carline being not less than double the length of the pitched portion thereof so that when the carline is straightened out a pitched roof is still maintained.
15. The combination with a car roof pitched from ridge to eaves, of a carline comprising a unitary structure extending from eave to eave and having its outer portions conforming to the pitch of the roof and its central portion below and spaced a considerable distance from the roof, means on said central portion for supporting the central portion of the roof, the total length of said carline being not less than double that of the pitched portion thereof to maintain a pitched roof when the carline is straightened.
